(57) **CLAIM**

The ornamental design for a two piece axe as shown and described herein.

DESCRIPTION

FIG. 1 is a front elevational view of the two piece axe, assembled to form a single axe, the back being a mirror image thereof;

FIG. 2 is a right side view thereof;

FIG. 3 is a left side view thereof;

FIG. 4 is a top view thereof;

FIG. 5 is a bottom view thereof;

FIG. 6 is a front right side perspective view thereof;

FIG. 7 is a front left side perspective view thereof;

FIG. 8 is a front left side bottom perspective view thereof;

FIG. 9 is a front right side bottom perspective view thereof;

FIG. 10 is a front elevational view of the two piece axe, disassembled into two pieces showing a short handle axe in the top portion of FIG. 10 and a separated handle extension portion in the lower portion of FIG. 10;

FIG. 11 is a right side view of the short handle axe and the separated handle extension portion as shown in FIG. 10;

FIG. 12 is a left side view of the short handle axe and the separated handle extension portion as shown in FIG. 10;

FIG. 13 is a front right side perspective view of the short handle axe and the separated handle extension portion as shown in FIG. 10;

FIG. 14 is a front left side perspective view of the short handle axe and the separated handle extension portion as shown in FIG. 10;

FIG. 15 is a front right side bottom perspective view of the short handle axe and the separated handle extension portion as shown in FIG. 10; and,

FIG. 16 is a front left side bottom perspective view of the short handle axe and the separated handle extension portion as shown in FIG. 10.
